UNITED STATES PATENT OFFICE

147,354

DESIGN FOR A CIGARETTE DISPENSER

Isaac B. Sherr, Los Angeles, Calif.

Application April 8, 1946, Serial No. 128,399

Term of patent 3½ years

(Cl. D85—2)

To all whom it may concern:

Be it known that I, Isaac B. Sherr, a citizen of the United States and a resident of Los Angeles, county of Los Angeles, State of California, have invented a new, original, and ornamental Design for a Cigarette Dispenser, of which the following is a specification, reference being had to the accompanying drawing, forming part thereof.

I claim:

The ornamental design for a cigarette dispenser, substantially as shown.

ISAAC B. SHERR.
